DESIGN FOR A TEXTILE FABRIC

Harry M. Goldman, New York, N. Y.

Application July 6, 1938, Serial No. 78,297

Term of patent 3½ years

To all whom it may concern:

Be it known that I, Harry M. Goldman, a citizen of the United States of America, residing in city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design. The drawing shows substantially one-half the width of the fabric, the upper half beginning with the upper horizontal dotted lines being the same but arranged in reverse order to complete the width of the fabric.

I claim:

The ornamental design for a textile fabric, substantially as shown and described.

HARRY M. GOLDMAN,
